UNITED STATES PATENT OFFICE.

JOHN E. LUNDQUIST, OF CHICAGO, ILLINOIS.

EXTENSION DEVICE FOR TABLES AND THE LIKE.

1,411,114.

Specification of Letters Patent. Patented Mar. 28, 1922.

Application filed March 31, 1920. Serial No. 370,097.

To all whom it may concern:

Be it known that I, JOHN E. LUNDQUIST, a citizen of the United States, residing at Chicago, in the county of Cook and State 5 of Illinois, have invented a certain new and useful Extension Device for Tables and the like, of which the following is a specification.

The invention has general reference to 10 tables, counters and like supports, and more particularly to an extension device in the nature of an attachment for such supports, by means of which the support may be made readily extensible, and which is mounted at 15 all times upon the support and is capable of being wholly concealed from view when the support is in its normal or unextended form.

An important object of the invention is to 20 provide an extension device of the character indicated which is capable of being readily attached to a support after it has been completed and gone into use as well as when the support is under construction.

Another object of the invention is to provide an extension device which is of extreme 25 simplicity so that it may be manufactured at a low cost, and which is at the same time of a practical and efficient character.

Another object of the invention is to provide means of an advantageous character for 30 rigidly locking the parts of the support when extended against further separation, so that the support may be conveniently 35 moved about from place to place as a whole even when the extension device is in its operative position.

Still another object of the invention is to 40 provide means for automatically separating the supplemental leaves of the extension device when the sections of the support are separated, to permit of the independent 45 swinging of the leaves into and out of operative position unrestricted by the interlocking pins carried by the edges of the leaves.

A further object of the invention is to 50 provide means for effecting the automatic movement of the leaves into their operative position as the sections of the support are separated.

Other objects and advantages of the invention will be apparent from the following 55 description, wherein the invention is illustrated and described with considerable detail in connection with an extension table. While the invention is thus illustrated and

described as applied to a table, it will be understood that it is readily applicable to other forms of support, it being only necessary in the case of supports not originally 60 made extensible to divide the same into two sections and provide extension slides of a standard character to which my invention may be readily applied.

In the drawings, Figure 1, is a side elevation of a table equipped with my invention. Fig. 2 is a perspective view showing the invention applied to the extension slides of the table but with the leaves of the extension device omitted for the sake of clearness. 70 Fig. 3 is a fragmentary top plan view of the table showing two leaves in their extended or operative position and two leaves in collapsed or inoperative position, it being assumed that the last mentioned leaves are 75 held against automatic extension by the operator. Fig. 4 is a transverse sectional view through the table taken on line 4—4 of Fig. 3. Fig. 4^a is a fragmentary sectional view showing the means for effecting the 80 automatic movement of the extension leaves or elements into operative position. Fig. 4^b is a similar view showing the parts in different relative positions. Fig. 5 is a similar view but showing the manner in which the 85 sections of the leaves are swingable into collapsed or inoperative position. Fig. 6 is a transverse sectional view taken on line 6—6 of Fig. 3 showing one of the leaves in its collapsed position. 90

Referring to Figs. 1 and 3 of the drawings, 1 and 1^a designate the two top sections of a table having my invention embodied therein. The table may be of any ordinary or preferred construction, having a sectional 95 top-supporting frame 2 mounted upon legs 3. Within the frame 2 are mounted suitable extension slides 4 of standard construction, each comprising a pair of members 5 and 6 secured respectively to the two sections of 100 the table and an intermediate member 7.

To the opposite intermediate members 7 I attach my extension device, which comprises a pair of cross-bars 8 and 8^a rigidly secured at their opposite ends to the ends of 105 the members 7 and connected to form a supporting frame. Said cross-bars carry a pair of brackets 9 upon which is supported a rod 10 having swingably mounted thereon one or more extension elements or leaves 11. 110 Herein I have shown four such elements.

The leaves 11 are made sectional in form,

comprising two substantially equal parts or sections 11^a and 11^b connected by means of a suitable hinge 12 preferably of the invisible type. One of the sections of the leaves, 5 herein section 11^b, has secured upon its under side a bracket 13 made of a strip of metal bent into generally U-shaped form and extending substantially across the entire width of the leaf. Said brackets are located 10 near the hinged ends of the sections 11^b so as to permit of the swinging of the leaves upon the rod 10 (Fig. 5).

The brackets 9 for supporting the rod 10 and thereby the leaves 11 through the medium of the brackets 13, are located at one side of the center of the table a distance corresponding to that between the end of the section 11^b and the bracket 13. Said brackets 15 9 and 13 are so proportioned that when 20 the sections of the leaves are swung into operative position their opposite ends rest upon the extension slides, which thus constitute spaced supporting members, with the upper surfaces of the leaves lying flush with 25 the upper surfaces of the top sections 1 and 1^a of the table; and when the leaves are 30 swung into their collapsed position as shown in Fig. 6 they assume a position somewhat below the table tops. In this latter position the free ends of the leaves are supported by 35 a longitudinal bar 14 secured at its opposite ends to the cross-bars 8 and 8^a and at the side of the center of the table opposite the rod 10.

For supporting the leaves 11 in their extended relation I provide for each leaf a pivoted locking arm 15. Said arms are mounted in brackets 16 carried by a longitudinal bar 17 which is secured at its opposite ends to the cross-bars 8 and 8^a substantially centrally thereof. At their upper ends 40 the arms 15 have bearing portions 15^a adapted to engage with the leaves adjacent their hinged joints (Fig. 4). As shown in said 45 figure, the arms 15 are mounted upon their brackets 16 at one side of their centers and the lower ends of the arms are adapted to engage with the upper surface of the bar 17 to limit the upward swinging movement of the 50 arms. In order that said arms will automatically swing into inoperative position when released by the initial movement of the leaf sections in the operation of swinging them into their inoperative positions, the bearing 55 portions 15^a of said arms are made of substantial length so as to cause the arms to swing by gravity from upright to horizontal position.

Upon the opposite edges of the leaves of 60 the top sections 1 and 1^a of the table are provided the usual pins and sockets 18 and 18^a, which serve to secure the leaves in operative relation when the table is extended. In order that said pins 18 shall not interfere with 65 the independent swinging movement of the

leaves upon the rod 10 I preferably arrange them in spaced relation and provide coiled springs 19 upon the rod 10 adapted to bear at their opposite ends against the adjacent ends of the brackets 13. Said springs are 70 made of sufficient tension only to properly space the leaves apart when the sections of the table are separated, being adapted to readily yield to permit the leaves to be moved together into their operative relation. 75

It will be observed that the cross bars 8 and 8^a connected by the bars 14 and 17 constitute a frame pivotally supporting the extension leaves and adapted to be quickly and easily secured to the intermediate sections 7 of the extension slides. This feature is of major importance since it enables the attachment of the device to tables in use, without a reconstruction thereof. 80

For the purpose of locking the parts of 85 the table in extended relation, permitting of the convenient movement of the table as a whole from place to place without danger of further separation, I provide locking means in the form of a telescoping rod 20. Said 90 rod consists of an inner section 20^a and a sleeve 20^b rigidly secured respectively to the two table sections as by means of brackets 21 (Fig. 1). A suitable number of supports 22 for the sleeve section 20^b are provided 95 upon the frame 2 of the table, and at the free end of the sleeve section 20^b is rigidly secured a collar 23 carrying a thumb-screw 24 which is operable into engagement with the rod section 20^a to lock the sections of the 100 rod together and hence secure the parts of the table against extension.

If it is desired that the sections of the leaves operate automatically from their collapsed position into extended relation, 105 this may be accomplished by means of a spring 25 which may be provided between the sections of each of the leaves 11 as shown in Figs. 4^a and 4^b. Said springs may comprise a central coil 25^a having oppositely 110 extending arms 25^b secured in the ends of the sections 11^a and 11^b, suitable sockets 26 being provided in the ends of the sections to receive the coil. For the purpose of normally holding the leaves in their collapsed 115 or folded position, a longitudinal member 27 is secured upon the under side of each of the top sections 1 and 1^a of the table (Fig. 6). These members are adapted to slidably engage with the upper sections 11^b of the 120 leaves as shown in said figure to hold it downwardly on the section 11^a and the latter upon its support 14. Suitable means such as an inclined member or guide 28 may be mounted upon the cross-bars 8 and 8^a and 125 the support 14 to assist the springs 25 in effecting the movement of the leaves into their operative position when such movement is permitted by the separation of the top sections 1 and 1^a. Said guide 28 may 130

be made of sheet metal, one edge being secured to the underside of the support 14 and the opposite edge mounted upon a rod 29 having its opposite ends 30 mounted on 5 the cross-bars 8 and 8^a.

It will be understood that the members 27 may be employed independently of the use of the springs 25 of the leaves, for holding the sections of the leaves together and 10 against movement as when the table is inverted or tilted upon its side during transportation.

Preferably, in order to prevent the leaf sections from warping, I provide upon the 15 under side thereof a plurality of metallic cleats 31. Herein one cleat is secured at each end of the leaf sections.

The supporting bar 17 for the locking arms 15 may also carry the central center 20 leg 3^a when such a leg is employed. Said bar, as shown in Fig. 5, has herein one edge beveled as at 17^a to permit of the unrestricted operation of the leaves.

It will be seen that I have provided means 25 enabling the quick and easy extension of a table or other support. The apparatus is of a very practical character in that it is extremely simple in construction and operation, and moreover in that it may be embodied in tables either in the course of construction or after they are completed and in use. At the same time, the leaves are adapted when in their operative or extended 30 position to provide a firm and rigid support, and the table when extended is capable of being locked into a rigid whole so that it 35 may be conveniently moved about as desired.

I claim as my invention:

1. A unitary extension device for attachment 40 to tables or the like having sectional slides for connecting two relatively movable table sections, said device comprising a frame fixed to and supported by one of the sections of each of said slides, a leaf formed 45 of two sections hinged together, and a rod mounted in fixed position upon said frame and supported solely thereby and to which one of said leaf sections is pivoted.

2. An extension device for extension tables 50 and the like having two relatively movable sections, supporting means for each of said sections, and sectional slides connecting said sections, said device comprising a frame fixed to and supported by sections of said 55 slides independently of said supporting means for the table sections, a stationary pivotal support carried solely by said frame, and a sectional leaf mounted upon said pivotal support.

60 3. The combination with a pair of sectional slides for extension tables and the like, each of said slides comprising two end sections and an intermediate section; of a 65 pivotal support, means rigid with and supported by said intermediate sections of the

slides providing a stationary mounting for said pivotal support, and a sectional leaf the sections of which are hinged together and mounted upon said pivotal support for movement from an inoperative position between the slides to an operative position with its opposite ends resting upon the slides. 70

4. The combination with a pair of extension slides for extension tables and the like 75 each comprising a pair of end sections and an intermediate section, of a pair of cross bars rigidly secured to and supported by the opposite ends of the intermediate slide sections, a rod mounted at its opposite ends 80 upon said cross bars, a leaf comprising two sections hinged together and mounted upon said rod for swinging movement from an inoperative or folded position between the slides to an operative or extended position 85 with its opposite ends resting upon the slides, a supporting member carried by said cross bars, and means adapted to be entered between said supporting member and said leaf when the latter is in its extended position to support it in extended position. 90

5. In combination with a sectional support and a pair of slides extensibly connecting the sections of the support together, of an extension device comprising a frame carried by said slides, a sectional extension element or leaf pivotally supported by said frame on an axis parallel to said slides so as to be operable from a position between the slides into operative position above the 95 slides with its opposite ends resting thereon, and means carried by the frame for locking the extension element in its operative position, the last mentioned means comprising a stop member pivoted at its lower end upon 100 the frame with its free end arranged to engage the under side of the leaf element and adapted to automatically move into inoperative position when released by a movement of the leaf element. 110

6. In combination with a sectional support and a pair of slides extensibly connecting the sections of the support together, of an extension device comprising a frame carried by said slides, a sectional extension element or leaf pivotally supported by said frame on an axis parallel to said slides so as to be operable from a position between the slides into operative position above the 115 slides with its opposite ends resting thereon, and a stop member pivotally mounted at its lower end upon the frame so as to be swung into upright position with its free end engaging beneath the extended leaf element or into inoperative position upon the support, 120 said member being automatically movable in one direction when released by the initial movement of the leaf element. 125

7. In combination with a support formed in two sections and having a pair of slides 130

- extensibly connecting them together, each slide consisting of a pair of members connected respectively to said sections of the support and an intermediate member, a pair 5 of cross-bars secured at their opposite ends to and supported by said intermediate slide members, a rod carried solely by said cross-bars, a plurality of sectional leaves the sections of which are hinged together and 10 swingably mounted upon said rod so as to be operable from a position beneath the rod to a position above it with the free ends of the sections resting upon the slides, a supporting member secured at its opposite ends 15 to said cross-bars, and a locking member for each of said sectional leaves carried by said supporting member and adapted to maintain the leaves in extended or operative position.
- 20 8. In combination with a support formed in two sections and having a pair of slides extensibly connecting them together, each slide consisting of a pair of members connected respectively to said sections and an intermediate member, a pair of cross-bars secured at their opposite ends to said intermediate slide member, a rod mounted at its opposite ends upon said cross-bars, a plurality of sectional leaves the sections of which are hinged together and swingably mounted 25 upon said rod so as to be operable from a position beneath the rod to a position above it with the free ends of the sections resting upon the slides, a supporting member secured at its opposite ends to said cross-bars, and a locking member for each of said sectional leaves adapted to maintain the leaves in extended or operative position, said leaves and sections of the support having interfitting pins and sockets, and yieldable means 30 arranged between the sectional leaves and adapted to space them apart to permit of their independent operation unrestricted by said pins.
- 35 9. The combination with a sectional extension table having a main support consisting of separate members movable away from each other when the sections are extended, and slides connecting the sections, of a unitary means wholly independent of said members constituting an auxiliary support, said means comprising a frame secured to and supported by said slides, and a folding sectional leaf pivotally mounted on said frame.
- 40 55 10. In a device of the class described, the combination of a pair of spaced supporting members, a plurality of sectional leaves swingably mounted on an axis disposed between said supporting members, said leaves being operable from a position below such axis to operative position above such axis with the free ends of the leaves resting upon 60 said supporting members, means mounted below the joint between the leaf sections and

adapted to support the center of the leaf, 65 said leaves having pins and sockets upon their edges adapted to interengage, and yieldable means between the several leaves normally spacing them apart to permit of their independent operation unrestricted by 70 said pins.

11. The combination with a pair of spaced supporting members, of a support extending between said members and having mounted thereon a rod extending parallel with said members, a plurality of leaves swingably mounted upon said rod and each comprising two sections hinged together, one of said sections having a bracket by means of which the leaf is mounted upon said rod, 75 means for supporting the sections of the leaves against flexing when swung into position with their opposite ends resting upon said supporting members, and spring means mounted upon said rod and bearing between 80 the brackets of the several leaves to space them apart whereby to permit of their free and unrestricted independent operation.

12. In a device of the class described, the combination with a support formed in two 90 sections having slides extensibly connecting them together, of a sectional extension element mounted to swing on an axis between the slides and parallel thereto from an inoperative or folded position to an operative 95 or extended position with its opposite ends resting upon said slides, the sections of said element being hingedly connected together and having at said connection a spring normally tending to move the sections of the 100 element into extended relation, and means carried by one section of the support adapted to hold said element against movement under the action of said spring.

13. In a table or the like, the combination 105 with a support formed in two sections, and means extensibly connecting the sections together, of a frame carried by the connecting means, a plurality of sectional leaf elements mounted upon the frame so as to be swingable 110 from an inoperative or folded position to operative or extended position in alignment with the tops of the sections, said extension elements and the section tops having interengaging pins and sockets, spring means for yieldably spacing said leaf elements and said sections apart to permit of the independent movement of the elements, 115 and means for locking the sections of the support together with one or more of the extension elements in operative position therebetween.

14. In a table of the class described, the combination with a support formed in two sections extensibly connected together, of an auxiliary support element adapted to be positioned between the tops of the sections, and means for locking the sections together with 125

said auxiliary element interposed therebetween, said means comprising a pair of telescoping members secured respectively to the sections of the support, and a device for securing said telescoping members together in fixed relationship.

15. The combination in a table or like support having two relatively movable sections, of a pair of slides extensibly connecting said sections together and each comprising a pair of end sections and an intermediate section, means rigid with and supported solely by said intermediate sections of the slides providing a stationary pivotal support, a leaf formed in two sections hinged together mounted upon said pivotal support for swinging movement from a position between said slides to an extended position with its opposite ends resting upon the slides, 20 and means for supporting said leaf in its extended or operative position.

16. The combination of a pair of sectional slides for connecting two table sections together, each comprising a pair of end sections and an intermediate section, a pair of cross bars secured at their opposite ends to the opposite ends of said intermediate slide sections, a rod mounted upon said cross bars and disposed longitudinally between the 25 slides, and a leaf formed in two sections hinged together and mounted upon said rod so as to be swingable from an inoperative position below the rod to an operative or extended position above the rod with its opposite ends resting upon said slides, the 30 hinged ends of said leaf sections being adapt-

ed to swing between and below said cross bars in the swinging movements of the leaf.

17. The combination in a table or like support having two relatively movable sections 40 and a pair of sectional slides connecting said sections together and each comprising a pair of end sections and an intermediate section; of a pair of cross bars secured at their opposite ends to the opposite ends of said intermediate slide sections, a rod mounted upon said cross bars and disposed longitudinally between the slides, a leaf formed in two sections hinged together and mounted upon said rod so as to be swingable from an inoperative position below the rod to an operative or extended position above the rod with its opposite ends resting upon said slides, the hinged ends of said leaf sections being adapted to swing between and below 45 said cross bars in the swinging movement of the leaf, and a support carried by said cross bars and having means adapted to support the leaf in its extended position, said support being located so as to permit of the unrestricted swinging movements of the leaf.

18. An extension table having, in combination, two table-top sections movable toward and away from each other, slides connecting the sections, a frame secured to and supported by said slides, a plurality of folding sectional leaves pivotally mounted on said frame, and springs located between the leaves and tending to move the leaves apart.

In testimony whereof, I have hereunto set 70 my hand.

JOHN E. LUNDQUIST.
